UNITED STATES PATENT OFFICE.

ROBERT A. GALLY, OF CINCINNATI, OHIO, ASSIGNOR TO THE BALDWIN COMPANY, OF CINCINNATI, OHIO.

MUSIC-SHEET-REGULATOR THROW-OUT.

1,269,071.

Specification of Letters Patent. Patented June 11, 1918.

Application filed August 18, 1917. Serial No. 186,980.

To all whom it may concern:

Be it known that I, ROBERT A. GALLY, a citizen of the United States, and residing at Cincinnati, in the county of Hamilton and 5 State of Ohio, have invented certain new and useful Improvements in Music-Sheet-Regulator Throw-Outs, set forth in the annexed specification.

In applicant's prior Patent #1,093,046 is 10 the broad invention of means to alternately make effective either automatic means or manually controlled means of a web guiding device, and one particular form was therein shown. The present invention shows an 15 other desirable form for use with many styles of web guiding or automatic tracking devices, and especially so with the novel form of automatic tracking device illustrated herewith, but which tracking device 20 *per se* is a part of a prior application #186229 filed August 14th 1917. The present application also sets out an extra feature whereby the detector fingers of the automatic device are thrown out of contact with 25 the edges of the music during the use of the hand regulator, thereby avoiding interference and friction from the combined action of the two means at one time.

In the drawings Figure 1 is a front view 30 of a music roll apparatus and combined automatic tracking device and hand roll regulator, the hand regulator thrown out of use, and the automatic tracking fingers contacting the two edges of the music sheet 35 and controlling the true travel of the sheet; and in Fig. 2 is the same view with the hand roll regulator thrown into use and the automatic tracking fingers thrown out from the edges of the music sheet.

40 Two usual clutch spindles 1 and 2 are adapted to engage and revolve a music roll 3 on which is mounted a music sheet as 4. Two vertical detector fingers 5 and 6 are mounted on pivots 7 and 8, and have inwardly extended horizontal arms 9 and 10 which nearly meet, and at such position of 45 adjacency coöperate with a valve seat 11 which is mounted on another horizontal arm 12, pivoted co-axially with arm 10. All 50 these arms, 9, 10 and 12 are extended beyond these pivots 7 and 8, and on such extensions are individual counterweights 13, 14, and 15. These several weights are so arranged that when the detector fingers 55 and 6 are to contact the edges of the music

sheet 4 the pressure of the detectors 5 and 6 will not be overstrong against that paper. Particular care is taken that the counter-balancing is so adjusted that the seat 11 will always follow the inner ends of the 60 arms 9 and 10, but that either one alone of the said arms 9 or 10 will have sufficient remaining weight to always rest on the seat 11 when the other arm 9 or 10 is away from the seat 11 when the music sheet is diverged 65 from its central travel.

When the sheet 4 is truly central the two detectors 5, 6, and their arms 9 and 10 both maintain contact with the seat 11, thereby controlling certain ports connected to any 70 usual pneumatic apparatus to actuate the shifting means to move the spindles 1 and 2 to the right or left to compel the central travel of the sheets whenever it diverges therefrom, and thereby thrusts one or the 75 other of the arms 9 and 10 away from the seat 11. The intermediate parts, as pneumatics, etc., are not here shown, but are to be understood as having tubular connections from ports in the seat 11 to any suitable 80 pneumatics, the latter having mechanical connections terminating by a rod 16 engaging a unitary means or yoke 17 similar to applicant's prior Patent #1,112,061 September 29, 1914, which yoke engages the two 85 spindles 1 and 2 and by suitable collars thereon and the spring 18 draws the two spindles together and thereby engages them with and holding the music roll 3, or any other suitable connecting and controlling 90 means may be employed.

Whenever a music sheet is found that has its perforations cut out of center to the correct travel line, or whose edges are too badly damaged to properly control the detectors 95 5, 6, the hand roll regulating devices can be thrown into operation, and the detectors may also be spread apart and clear of the edges of the sheet, as in Fig. 2, as will now be explained.

The spindle 2 runs in a regulator bearing 19 threaded co-axially therewith into a support 20. While in a structure without an automatic tracking device such a threaded regulator bearing 19 would directly regulate the position of the roll 3 by the said roll being pressed against the head 21 of the said spindle 2 and that head against the end of the regulator bearing, such a construction would interfere with the action of an 110

automatic tracking mechanism, which could not move the spindle 2 to the right because of the checking by its head 21 against the regulator bearing 19, wherefore the present structure has the regulator bearing 19 of a length to clear the head 21 of the spindle 2 so that the head 21 and its spindle 2 are free to be longitudinally moved by the automatic tracking means 17, 16, etc., as described in par. 2 of page 1.

When the hand regulating is desired, the switch or throw-out handle 22 is partly revolved with the shaft 23 on which it is fixed as shown in Fig. 2, thereby the circumferentially tapered cam 24 has its full width part brought around within a groove in the collar 25 attached on spindle 2, which wide part of the cam 24 has a nice running and guiding fit to the groove of the collar 25, thereby compelling the collar 25 and spindle 2 attached therewith, to maintain whatever position lengthwise of the spindle line that the cam 24 and its attached shaft 23 may be set to by control of a plain guide arm 26 and hub collar fixed with the shaft 23 and guided by a groove in a collar 27 attached to or a part of the regulator 19 and revoluble with said bearing 19 and thereby shiftable lengthwise of the spindle line to regulate any desired tracking position of the roll 3 and its music sheet 4, as shown by the dotted lines in Fig. 2 indicating the rightward position of the regulator parts, the full lines being the leftward position.

When the apparatus has the switch handle 22 set for hand regulating, which in the present showing is with the handle 22 thrown over to the front and down, an extension or arm 28 is pressed down on the head 29 of a vertical rod 30, which rod 30 stands over the counterweight 15 or other convenient and suitable part of the seat arm 12, thereby depressing that outer end of the seat arm 12 and raising the seat 11, and thus lifting the two arms 9, 10, and throwing apart the two detector arms 5, 6, so that their detector parts clear the edges of the music sheet and thus have the sheet free, and avoid any actuating of the automatic tracking devices 50 against the setting of the spindles by the hand regulator, which actuating at such time would cause great retarding or entire stopping of the spindles from the pressure of the automatic tracking motor means against the regulated spindle. When the detectors 5, 6, are so spread, and the seat 11 is in a raised position, both the arms 9, 10, are held on the said seats, so that the entire automatic tracking devices are out of operation, and free for the longitudinal regulating of the spindle 2 by the hand regulator 19. A spring 31 serves to hold the rod 30, free from the weight 15 and arm 12 when the throw-out handle 22 is in position for the automatic tracker devices to operate.

When the throw-out handle 22 is set for the operation of the automatic tracking devices, the narrow part of the cam 24 is between the sides of the groove of the collar 25 so that the wider part of the cam may be sure to follow to position in that groove when revolved to that position by the handle 22 and the shaft 23, but the difference in width between the narrow part of the cam 24 and the groove of the collar 25 must be sufficient to allow for the full amount of any automatic tracking movement of spindle 2 and its collar 25, and added thereto the amount of regulating movement of the hand regulator, so that if the hand regulator is left set to either extreme when the automatic tracking is used, the latter will be free.

Any style of web guiding or automatic tracking device may utilize the present invention, whether such device employs edge control fingers or surface control contacts or apertures, and whether pneumatic, electric or mechanical power, or any combination of powers, as pneumatic mechanical or the like, but what I claim as my invention is:—

1. A revoluble spindle adapted to engage a music roll; a collar fixed with the said spindle and a circumferential groove in the said collar; a revoluble shaft parallel with the said spindle; a cam fixed on said shaft and having its outer part standing between the sides of the groove of the said spindle collar, and the said outer part of the cam of approximately the full width of the said groove at one revolved position of the said shaft and cam, and of much less than the width of the said groove at another revolved position of the said cam; means adapted to revolve the said shaft and its cam to their two above stated positions; and means adapted to move the shaft and its cam to several positions in the direction of the length of the said shaft spindle..

2. A revoluble spindle adapted to engage a music roll; a collar fixed with the said spindle and a circumferential groove in the said collar; a revoluble shaft parallel with the said spindle; a cam fixed on said shaft and having its outer part standing between the sides of the groove of the said spindle collar, and the said outer part of the cam of approximately the full width of the said groove at one revolved position of the said shaft and cam, and of much less than the width of the said groove at another revolved position of the said cam; means adapted to revolve the said shaft and its cam to their two above stated positions; and means adapted to move the shaft and its cam to several positions in the direction of the length of the said shaft spindle when the said cam is in its said position of its wider part engaging the groove in the said collar.

3. A revoluble spindle adapted to engage

a music roll; a collar fixed with the said spindle and a circumferential groove in the said collar; a revolute shaft parallel with the said spindle; a cam fixed on said shaft and having its outer part standing between the sides of the groove of the spindle collar, and the said outer part of the cam of approximately the full width of the said groove at one revolved position of the said shaft and cam, and of much less than the width of the said groove at another revolved position of the said cam; means adapted to revolve the said shaft and its cam to their two above stated positions; a revolute threaded regulator means having its axis in the same general direction as the axis of the said spindle and the said shaft; a circumferential groove in the said regulator means; and a collar fixed on the said shaft and revolute therewith and engaged in the said groove of the said regulator means.

4. A revolute spindle adapted to engage a music roll; a collar fixed with the said spindle and a circumferential groove in the said collar; a revolute shaft parallel with the said spindle; a cam fixed on said shaft and having its outer part standing between the sides of the groove of the spindle collar, and the said outer part of the cam of approximately the full width of the said groove at one revolved position of the said shaft and cam, and of much less than the width of the said groove at another revolved position of the said cam; means adapted to revolve the said shaft and its cam to their two above stated positions; a revolute threaded regulator means having its axis in the same general direction as the axis of the said spindle and the said shaft; a circumferential groove in the said regulator means; and a collar fixed on the said shaft and revolute therewith and engaged in the said groove of the said regulator means; and means adapted to revolve the said shaft to the two said positions of the said cam.

5. Means for propelling a web; hand controlled means adapted to regulate the travel

of the said web to a true line of travel; automatic means adapted to regulate the travel of the said web to a true line of travel, the 50 said automatic means including a detector finger adapted to contact an edge of the said web during the operation of the said automatic means; means adapted to alternatively make effective the said hand controlled means and the said automatic means and to remove the said detector finger from contact with the said web when set for the operation of the said hand controlled means. 55

6. Means for propelling a web; hand controlled means adapted to regulate the travel of the said web to a true line of travel; automatic means adapted to regulate the travel of the said web to a true line of travel, the 60 said automatic means including two detector 65 fingers adapted to contact the two edges of the said web during the operation of the said automatic means; means adapted to alternatively make effective the said hand controlled means and the said automatic 70 means and to remove the said detector fingers from contact with the said web when set for the operation of the said hand controlled means.

7. Means for propelling a web; hand controlled means adapted to regulate the travel of the said web to a true line of travel; automatic means adapted to regulate the travel of the said web to a true line of travel, the 75 said automatic means including two detector 80 fingers adapted to contact with both edges of the said web during the operation of the said automatic means; means adapted to alternatively make effective the said hand controlled means and the said automatic 85 means and to spread the said two detector fingers away from each other and from contact with the said web when set for the operation of the said hand controlled means.
